UNITED STATES PATENT OFFICE.

FRANK D. SHEPHERD, OF SALT LAKE CITY, UTAH.

PUPPET-VALVE FOR INTERNAL-COMBUSTION ENGINES.

1,240,378.

Specification of Letters Patent. Patented Sept. 18, 1917.

Application filed February 8, 1917. Serial No. 147,397.

To all whom it may concern:

Be it known that I, FRANK D. SHEPHERD, a citizen of the United States, and resident of Salt Lake City, in the county of Salt Lake and in the State of Utah, have invented a certain new and useful Improvement 5 in Puppet-Valves for Internal-Combustion Engines, and do hereby declare that the following is a full, clear, and exact description thereof.

My invention relates to puppet valves and especially those adapted for use with internal combustion engines, and my object, generally stated, is to provide a valve construction 15 which will increase the power of the engine, or to put it differently, will secure economy of use of fuel; which will efficiently and certainly perform its functions of closing and opening, so that when closed 20 upon its seat it can be depended upon to cut off completely the flow of gas, and when open will allow free and ample passage; will be simple of construction, hence contributing to economy of manufacture as well as 25 eliminating danger of becoming disordered; and will be readily and easily accessible for removal and replacement of the parts, whose removal and replacement may be desirable, and for the attainment of this 30 object and others which will be understood by those skilled in the art when the characteristics of the valve embodying my invention are understood from the accompanying drawings and description, my invention 35 consists in the valve mechanism constructed substantially as hereinafter specified and claimed.

In the accompanying drawings which illustrate several forms, or embodiments of 40 my invention—

Figure 1 is a vertical section through an internal combustion engine having a valve embodying my invention;

Fig. 2 is a similar view, but showing only 45 the valve mechanism and immediately adjacent parts of another embodiment of my invention;

Fig. 3 is a view similar to Fig. 2, but illustrating a different construction.

50 Giving a detail description of the construction shown in Fig. 1 of the drawing, the engine cylinder 10 shown is of the type having the head 11 cast integral therewith and connected with said head there are as 55 many puppet valves, as, in the judgment of the designer it is proper, or desirable to

employ, but for the purpose of disclosing my invention to those skilled in the art it is not necessary to show and describe more than one valve mechanism, which thus 60 is to be taken as representative, or typical for both the intake and the exhaust, and for as many as it may be desirable, or expedient to employ. My invention, as will be evident, has to do with the valve construction 65 and not with the number employed (although its construction is such as to render unnecessary multiplication of the number); nor is my invention concerned with the particular type, or construction of 70 the engine, or the mechanism for lifting the valve from its seat. In the engine head eccentric to the cylinder, I provide an internally threaded opening 12 which extends from the outer end of the head into the port 13, 75 which is controlled by the valve mechanism, for which purpose, directly in line with said opening 12 and on the opposite side of the port it has a beveled seat 14 for the puppet valve 15 whose face, or rim is correspond- 80 ingly beveled so that it closely, and in a gas tight manner, fits its seat. Screwed in said hole 12 is one end of a cylindrical shell 16, a gas tight joint being formed between a shoulder on said shell and the outer side of 85 the cylinder head by an interposed washer, or gasket 17. When the outer end of said shell is closed in a gas tight manner by a plug 18 which is screwed into said outer end and a gas tight joint formed by a 90 washer, or gasket 19 clamped between the plug and a shoulder, or bearing on the shell. At the opposite inner end of the shell it is closed save for a central hole 20 through which passes, with a sliding fit, a stem 21. 95 Said stem extends from the valve and into the chamber in said shell and within the chamber it has a flange, or head 22 of substantially the diameter of the chamber, and between said head and an abutment, or 100 bearing surface is interposed an expansive coil spring 23, which by pressure on the valve transmitted through said head and stem yieldingly holds the valve to its seat from which it is lifted by the usual lifter 105 cam 24 acting through a stem 25 on the opposite side of the valve from the stem 21. The stem 21 is not connected with, or attached to the valve and it need not be because it acts by thrust upon the valve, but 110 at its inner end it simply bears against the outer side of the valve and preferably as

shown in Fig. 1, a ball and socket bearing between the stem and valve is provided, the socket 26 being provided in the valve and the ball being formed by rounding the end 5 of the stem. Thus the stem 21 affords support for the valve against lateral movement and there is such contact of stem and valve that on an explosion in the engine cylinder no gas can act upon the end of the 10 valve stem with a lifting force and yet the advantages coming from the separate connection of stem and valve are secured.

Means, such as several holes 27, are provided in the outer face of the valve for the 15 application thereto of a suitable tool for grinding the valve while on its seat.

The flange, or head 22 has a spring-engaging surface that is preferably concave, or dished so as to afford a good bearing for the 20 spring and within the spring it has a short extension over which the spring loosely fits, and from end to end it is perforated as by means of several holes 28 whose purpose is to prevent such suction between the inner 25 sides of the head and the adjacent stationary surface as would hinder, or obstruct perfectly free movement of the head and of the valve when the latter is lifted from its seat and to prevent the existence of an air 30 cushion that would obstruct, or hinder the seating movement of the valve. Between the head 22 and the inner end of the shell 16 is a ring 29 of absorbent fire-proof, or non-heat conducting material which snugly fits 35 the annular space around the valve stem 21, and said ring being saturated with some lasting lubricant, it supplies such lubricant to the valve stem and thus eases its movements in the hole in the inner end of the 40 shell 16. Moreover said ring 29 also performs the function of packing the joints so as to prevent the leakage, or escape of gas into the shell 16, and when made of non-heat conducting material it protects the 45 spring within the shell 16 from the high temperatures of the gas passing through the port 13.

To reduce the unoccupied space, or volume in the shell 16 to a minimum and thus 50 preclude the presence in said shell of any more than a negligible quantity of gas, should leakage into the shell 16 occur, the plug 18 has an inward cylindrical extension 55 that constitutes a filler within the spring coils which is made as large in diameter and of as great length as possible without interfering with the play of the spring and the movements of the valves. Said extension, as shown in Fig. 1, has a threaded connection 60 with the plug 18 by means of a shank 31 which engages a threaded axial hole 32 in the plug, and upon said extension within the casing 16 is an annular flange 33 which forms the bearing for the outer end of the 65 coil spring 23. By this adjustable connec-

tion thus provided between the filler 30 and the plug 32, the tension of the spring 23 may be adjusted and also such adjustment of the plug made as is necessary to secure proper clearance, or avoidance of contact 70 between the inner end of the filler and outer end of the valve stem. Preferably said filler 30 and its threaded shank are hollow so as to render the heat radiating surface of as great an area as possible and thereby safeguard the spring from injury by high temperatures and the outer end of the chamber at least may be made flat-sided for the reception and engagement of a suitable socket wrench for turning for adjustment. Of course, at its inner end the filler 30 is closed 80 since an important characteristic of my invention is the preservation of a gas-tight condition within the shell 16, which is completely cut off from communication with the external atmosphere. A lock nut 34 is applied to the threaded shank 31 of the filler 30 so as to securely hold the parts at the desired adjustment.

As a further precaution against undue 90 heating, the radiating surface of the shell 16 may be increased by the familiar device of fins or ribs on its exterior.

Referring to the construction shown in Fig. 2, it will be found to differ from what 95 is shown in Fig. 1, in that the contacting surface of stem 210 and valve are flat, or plane, and in that the filler 301 is integral with the spring-engaging head 220 and with the valve stem 201, and said filler 301 is solid and in that the closing plug 181 affords the bearing for one end of the spring 23 and is provided with a wrench-receiving 100 socket 182.

The construction shown in Fig. 3 is similar to that shown in Fig. 1, excepting that the spring-engaging flange 33 shown in Fig. 1 is omitted, the plug 302 and its shank 303 are solid and an angular lug 304 projects from the shank for the application of a 110 turning wrench. The adjustment of the plug 302 in the case of the construction shown in Fig. 3, is simply to provide for proper clearance between the inner end of the plug and the outer end of the valve 115 stem 21, for in this case the spring 23 at its outer end bears against the closing plug 18.

I have shown various forms, or embodiments of my invention in order that it may be understood that I realize that such invention may exist in different forms. It, of course, can have embodiments other than those selected by way of example and, hence, it is to be understood that I regard myself as entitled to its embodiments in still other 125 forms than those shown in the drawings.

Having thus described my invention what I claim is—

1. The combination of an engine cylinder having a valve-controlled passage with a 130

valve seat, a puppet valve, a shell or container, a spring in said shell, a stem reaching from the valve into said shell, and a spring-engaging head on said stem, said 5 stem and said valve being unconnected.

2. The combination of an engine cylinder having a valve-controlled passage with a valve seat, a puppet valve, a shell or container, a spring in said shell, a stem reaching 10 from the valve into said shell, and a spring-engaging head on said stem, said stem and said valve being unconnected, and one of said parts having a socket that receives the other part.

15 3. The combination of an engine cylinder having a valve-controlled passage with a valve seat, a puppet valve, a shell or container, a spring in said shell, a stem reaching from the valve into said shell, and a 20 spring-engaging head on said stem integral with said stem, said stem and valve being unconnected.

4. The combination of an engine cylinder having a valve controlled passage with a 25 valve seat, a puppet valve, a shell or container into which a valve-operating member extends, a coil spring in said shell bearing

against said member at one end, and an adjustable filler that extends partially through the coils of the spring. 30

5. The combination of an engine cylinder having a valve controlled passage with a valve seat, a puppet valve, a shell or container into which a valve-operating member extends, a coil spring in said shell bearing 35 ing against said member at one end, and an adjustable filler that extends partially through the coils of the spring, said filler having a bearing for the other end of the spring. 40

6. The combination of an engine cylinder having a valve controlled passage with a valve seat, a puppet valve, a shell or container into which a valve-operating member extends, a coil spring in said shell bearing 45 ing against said member at one end, and an adjustable filler that extends partially through the coils of the spring, said filler having a bearing for the other end of the spring, and said filler being hollow and 50 opening to the external air.

In testimony that I claim the foregoing I have hereunto set my hand.

FRANK D. SHEPHERD.
